Application filed June 22, 1922. Serial No. 2,760. Term of patent 7 years.

To all whom it may concern:

Be it known that I, ETHELYN A. The essential feature of my design consists in providing a hat having a brim and a crown, the crown being formed of a plurality of darts with open spaces between them, and having ties for bridging the hair of the wearer.

I claim:

The ornamental design for a hat substantially as described and shown.
